UNITED STATES PATENT OFFICE.

HUBERT DALTON, OF NEW YORK, N. Y.

SHAFT-HANGER.

1,114,124.

Specification of Letters Patent. Patented Oct. 20, 1914.

Application filed March 28, 1914. Serial No. 827,849.

To all whom it may concern:

Be it known that I, HUBERT DALTON, a citizen of the United States of America, and resident of New York, in the county of New

5 York and State of New York, have invented certain new and useful Improvements in Shaft-Hangers, of which the following is a specification.

This invention relates broadly to improvements in power-transmitting apparatus, and more particularly concerns itself with the provision of means of the above general type adapted for advantageous employment in connection with the transmission of comparatively small power, as that generated from the operation of a foot-treadle.

One of the objects thereof is to provide a simple and practical hollow columnar housing for an operative interconnection between 20 what may be termed the driving and the driven members.

A collateral object is to combine in the same housing an interior chamber for the accommodation of said interconnection, a 25 supporting pillar for carrying thereon the working parts to be actuated by or through said driven member, and a sufficiently fixed and rigid support for a hanger or supporting means for said driven member.

30 Another object is to provide a unitary structure in the nature of a hanger, preferably of such a type that the same may be cast as one part, adapted to support a revolvable shaft to carry said driven member, and 35 also adapted to support in addition if desired means capacitated frictionlessly to carry the shaft for revolution relatively of the hanger,—characterized in this that said hanger as cast will not require an extensive 40 amount of machining and in this also that a relatively small amount of metal is used for the upbuilding of said hanger.

Another object is so to conform said hanger and its supported parts that they 45 may be entirely assembled as a combination complete in itself, before mounting the hanger permanently in position.

Another object is to provide a general supporting and power-transmitting structure 50 for utilization in connection with machinery of any type, which shall have as marked advantages the presence of an exceedingly small number of parts, great simplicity of construction, extreme inexpensiveness as to the producing cost of each of said parts, and 55 rigidity, reliability and sturdiness of con-

struction, as well as accessibility of the moving parts for repairs, oiling, adjustment, attachment and removal, not attained heretofore.

Other objects and aims of the invention, more or less broad than those stated above, together with the advantages inherent, will be in part obvious and in part specifically referred to in the course of the following 60 description of the elements, combinations, arrangements of parts, and applications of principles constituting the invention; and the scope of protection contemplated will appear from the claims.

In the accompanying drawing, which is to be taken as a part of this specification, and in which I have shown one of the various possible embodiments of the invention as at present preferred, Figure 1 is a side 70 elevation, partially broken away and partially in section, showing a preferred embodiment of the invention; Fig. 2 is a front elevation, partially broken away and partially in section, of said embodiment; Fig. 3 75 is a vertical sectional view, taken on the line 3—3 of Fig. 2; and Fig. 4 is an enlarged detail view of several of the parts the locations of which in Fig. 2 are indicated in broken-lines.

Similar reference characters refer to similar parts throughout the several views of the drawing.

Referring now particularly to the construction shown in the drawing, 5 represents 90 a hollow vertical column which may support upon the integral upper or table-leaf 6 thereof a base-board or supporting table 7 (indicated in broken-lines) adapted to carry a suitable burden, as the bedplate or feet of 95 a lathe or other machine, or said column may directly support said lathe or other machine. Column 5 at its lower end carries an integral foot-plate 8, preferably of sufficient dimensions to capacitate the column singly to support the lathe or other selected 100 superstructure. And it is this column 5 which here directly supports the hanger 9. The hanger when mounted in place partially extends into the chamber 10 within 105 the column and partially projects exteriorly of the latter; a vertical wall of the column being provided with an opening 11 and bosses 11' with which said hanger is associated as shown and as hereinafter described.

Hanger 9 consists of a unitary casting 110 conformed as shown, provided with a longi-

tudinal bore 12 which throughout its length is of a diameter preferably greater than the diameter of the shaft associated therewith. The hanger, intermediately of its length, is 5 provided with an integral flange-plate 13, preferably of a substantially elliptical form as shown in Figs. 1 and 3, adapted to permit of said flange-plate being placed overlapping of opening 11 and of the anchoring 10 of the hanger in position upon the column 5; the bolts 14 being present for the latter purpose. It will be seen immediately that the hanger is of an exceedingly simple and sturdy construction, consisting primarily of 15 said flange-plate 13, a tubular casing 15 (for establishing the bore 12 and the recess 16), an annular member 17, carrying a recess 18, and the two T-struts 19 (see Fig. 3) which serve to mount the annular member 20 17 upon and space the same predeterminedly away from said flange-plate.

Mounted in each of the recesses 16 and 19, as indicated in broken-lines in Fig. 2, and as shown in enlarged detail in Fig. 4, is a 25 ball-bearing device of a well-known commercial type. These devices in themselves form no part of the subject matter of the present invention. Each of the devices includes a shaft-contacting ring 20, a coöperant ring 21, a ball-race established between the rings, a plurality of balls 22 movable in said race, and an annular containing shell 23. The devices are maintained in their respective recesses preferably by means 30 merely of a suction or press fit. Shaft 24 is revolvably mounted within the hanger as shown, and preferably is closely gripped by the rings 20.

A pulley 25, which has hereinbefore been 40 referred to as the driven member, is fixedly carried by the shaft, the screw 26 being present for the purpose. The shaft also fixedly carries a crank-arm 27. The crank-arm is provided with an off-set stud 29 upon which 45 is pivotally mounted one terminus of a pitman 28, the other end thereof being adjustably and rigidly coupled, as by means of the nut 28', with a bifurcated link-member 30 pivotally attached to the treadle 31 as indicated. Treadle 31 is itself pivotally mounted within a trunnion-extension 32 cast integrally with the housing 5; the foot-plate of the treadle projecting from the housing by way of the opening 33. The 55 housing is also provided with a swinging door 34 which may be opened to expose a suitable opening in the housing, thus to obtain convenient access to the interior of chamber 10 for repairs, oiling, adjustment, 60 attachment and removal of any of the parts located interiorly of the chamber. A belt may of course be suitably associated with pulley 25 and extend upwardly to transmit power from said pulley to a cone-pulley or 65 the like forming a part of the particular

superstructure which may be supported by the housing.

The operation of this embodiment of the invention should be so obvious from the foregoing description of the details of its construction that further mention thereof should be unnecessary. But some space here should be given to a description of a preferable method of, first, building up as a complete unit the hanger 9 and its supported parts, and, next, mounting said hanger upon the housing and coupling up the pitman 28. The hanger 9, if constructed as a casting, is preferably given no machining whatever except perhaps a subjection to a reamer or drill-press to true up the recesses 16 and 18. The ball-bearing devices are then inserted in these recesses, the shaft 24 is arranged longitudinally of the hanger, and pulley 25 is fixedly attached to the shaft at such a point 75 longitudinally thereof as to predetermine a proper protrusion from the hanger of the opposite terminus of the shaft, upon which terminus crank-arm 27 is then fixedly mounted. The pulley and the crank-arm 80 as thus associated will coöperate to prevent longitudinal shifting of the shaft relatively of its hanger and also to prevent any accidental displacement of the ball-bearing devices. The collection of parts so assembled 85 into one complete operative unit are ready for permanent support upon the housing. And at this point attention may be called 90 to the substantially elliptical opening 11 and to the characteristic construction of that 95 portion of the hanger which in Fig. 2 is disclosed as located rightwardly of flange-plate 13. For it is of great practical advantage to construct the housing 5 with 100 horizontal dimensions one of which (such as that indicated by the double-pointed arrow 35 shown in Fig. 1) shall be considerably less than another of which (as indicated by the double-pointed arrow 36 of Fig. 2). Now the opening 11 is preferably 105 formed in one of the narrower of the two sets of vertical walls which partially establish the housing. Yet the opening must be 110 so conformed that there may be inserted therethrough for accommodation within the chamber 10 not only the portion of the hanger 9 which supports the annular member 17 but also the crank-arm 27; and at the 115 same time the last-mentioned portion of the hanger must be, whatever the exigencies of its cross-section design, as strong and rigid 120 as if of a hollow cylindrical type. In this connection, attention is called to the important feature which resides in the fact 125 that as aforesaid merely the T-struts 19 serve to mount the annular member 17 upon and spaced predeterminedly away from flange-plate 13, the result being that this portion of the hanger is exceedingly sturdy 130 and yet is possessed of what may be termed 135

an elliptical composite cross-section the minor axis of which is substantially coincident with the minor axis of opening 11 and the major axis of which is substantially coincident with the major axis of said opening. Attention is called to the fact, too, that the crank-arm, when arranged to upstand vertically from the shaft, is of such a length that it may be passed easily through the opening. When the flange-plate 13 of the hanger, carrying as above the shaft, pulley and crank-arm, has been anchored in place by means of the bolts 14 (and here attention may be called to the fact that neither the flange-plate nor the portion of the housing which surrounds the opening 11 need be given any machining), the pitman 28 is inserted within chamber 10 and is suitably pivotally connected with stud 29. The treadle 31, having been preferably inserted through the opening 33, is properly mounted in the trunnion-extension 32; and the lower end of the pitman is adjusted and rigidly connected to the link-member 30.

It will thus be seen that I have provided an embodiment of the invention well calculated to attain the various ends and objects thereof, and an embodiment, moreover, that is exceedingly practical, reliable of operation and convenient and economical of shop-space. While the embodiment disclosed is of the foot-power type, it is obvious that a motor could directly drive the shaft 24 or otherwise be suitably coupled therewith, the motor in either event being completely located interiorly of the housing, and an additional door or doors being provided if desired for access thereto.

Inasmuch as many changes could be made in the above construction, and many apparently widely different embodiments of my invention could be made without departing from the scope thereof, it is intended that all matter contained in the above description or shown in the accompanying drawing shall be interpreted as illustrative and not in a limiting sense. It is also to be understood that the language used in the following claims is intended to cover all the generic and specific features of the invention herein described and all statements of the scope of the invention which, as a matter of language, might be said to fall therebetween.

I claim:

1. In apparatus of the class described, in combination with a vertical support having a vertically elongated transverse aperture, a horizontally arranged and readily demountable shaft-hanger normally mounted upon said support and having a portion projecting from said support, the said portion including an integral structure comprising a horizontally-bored cylindrical member adapted to sleeve a shaft mounted within the hanger, said integral structure

also comprising a plate directly mountable upon said support, and said integral structure also comprising a pair of substantially horizontal struts one end of each of said struts being joined to said cylindrical member and the other end of each of said struts being joined to said plate thereby to support said cylindrical member and yet space the same from said support, one of said struts overlying said shaft and the other of said struts lying below said shaft, a cross-section through the first-mentioned strut defining an upright triangle and a cross-section through the second-mentioned strut defining an inverted triangle. 70

2. In apparatus of the class described, in combination with a vertical support having a vertically elongated transverse aperture, a horizontally arranged and readily demountable shaft-hanger normally mounted upon said support and having a portion projecting from said support, the said portion including an integral structure comprising a horizontally-bored cylindrical member adapted to sleeve a shaft mounted within the hanger, said integral structure also comprising a plate directly mountable upon said support, and said integral structure also comprising a pair of substantially horizontal struts, one end of each of said struts being joined to said cylindrical member and the other end of each of said struts being joined to said plate thereby to support said cylindrical member and yet space the same from said support, one of said struts overlying said shaft and the other of said struts lying below said shaft, a cross-section through the first-mentioned strut defining an upright triangle and a cross-section through the second-mentioned strut defining an inverted triangle, the bases of said triangles being parallel. 90

3. In apparatus of the class described, in combination with a vertical support having a vertically elongated transverse aperture, a horizontally arranged and readily demountable shaft-hanger normally mounted upon said support and having a portion projecting from said support, the said portion including an integral structure comprising a horizontally-bored cylindrical member adapted to sleeve a shaft mounted within the hanger, said integral structure also comprising a plate directly mountable upon said support, and said integral structure also comprising a pair of substantially horizontal struts one end of each of said struts being joined to said cylindrical member and the other end of each of said struts being joined to said plate thereby to support said cylindrical member and yet space the same from said support, one of said struts overlying said shaft and the other of said struts lying below said shaft, a cross-section through the first-mentioned strut defining 110

115

120

125

130

an upright triangle and a cross-section through the second-mentioned strut defining an inverted triangle, the bases of said triangles being parallel and spaced above and below said shaft.

5 4. In apparatus of the class described, in combination with a vertical support having a vertically elongated transverse aperture, a horizontally arranged and readily demountable shaft-hanger normally mounted upon said support and having a portion projecting from said support, the said portion including an integral structure comprising a horizontally-bored cylindrical member 10 adapted to sleeve a shaft mounted within the hanger, said integral structure also comprising a plate directly mountable upon said support, and said integral structure also comprising a pair of substantially horizontal struts one end of each of said struts 15 being joined to said cylindrical member and the other end of each of said struts being joined to said plate thereby to support said cylindrical member and yet space the same from said support, one of said struts overlying said shaft and the other of said struts lying below said shaft, the first-mentioned strut being of an inverted T cross-section and the second-mentioned strut being of a 20 T cross-section.

25 5. In apparatus of the class described, in combination with a vertical support having a vertically elongated transverse aperture, a horizontally arranged and readily demountable shaft-hanger normally mounted upon said support and having a portion projecting from said support, the said portion including an integral structure comprising a horizontally - bored cylindrical member 30 adapted to sleeve a shaft mounted within the hanger, said integral structure also comprising a plate directly mountable upon said support, and said integral structure also comprising a pair of substantially horizontal struts one end of each of said struts being joined to said cylindrical member and the other end of each of said struts being joined to said plate thereby to support said cylindrical member and yet space the same 35 from said support, one of said struts overlying said shaft and the other of said struts lying below said shaft, a cross-section through the first-mentioned strut defining an upright triangle and a cross-section 40 through the second-mentioned strut defining an inverted triangle the vertical distance in a given plane between the upper and lower limits of said portion being less than the horizontal distance in the same plane between the side limits of said portion.

45 6. In apparatus of the class described, in combination with a vertical support having a vertically elongated transverse aperture, a horizontally arranged and readily demountable shaft-hanger normally mounted

50 upon said support and having a portion projecting from said support, the said portion including an integral structure comprising a horizontally-bored cylindrical member adapted to sleeve a shaft mounted within the hanger, said integral structure also comprising a plate directly mountable upon said support, and said integral structure also comprising a pair of substantially horizontal struts one end of each of said struts 55 being joined to said cylindrical member and the other end of each of said struts being joined to said plate thereby to support said cylindrical member and yet space the same from said support, one of said struts overlying said shaft and the other of said struts lying below said shaft, a cross-section through the first-mentioned strut defining an upright triangle and a cross-section 60 through the second-mentioned strut defining an inverted triangle the vertical distance in a given plane between the upper and lower limits of said portion being less than the horizontal distance in the same plane between the side limits of said portion, the diameter of said member being less than the maximum horizontal dimension of said vertically elongated aperture whereby said portion may be inserted through said aperture to project from said support as aforesaid.

65 7. In apparatus of the class described, in combination with a vertical support having a vertically elongated transverse aperture, a horizontally arranged and readily demountable shaft-hanger normally mounted 70 upon said support and having a portion projecting from said support, the said portion including an integral structure comprising a horizontally-bored cylindrical member adapted to sleeve a shaft mounted within the hanger, said integral structure also comprising a plate directly mountable upon said support, and said integral structure also comprising a pair of substantially horizontal struts one end of each of said struts 75 being joined to said cylindrical member and the other end of each of said struts being joined to said plate thereby to support said cylindrical member and yet space the same from said support, one of said struts overlying said shaft and the other of said struts lying below said shaft, a cross-section through the first-mentioned strut defining an upright triangle and a cross-section 80 through the second-mentioned strut defining an inverted triangle the vertical distance in a given plane between the upper and lower limits of said portion being less than the horizontal distance in the same plane between the side limits of said portion, the diameter of said member being less than the maximum horizontal dimension of said vertically elongated aperture whereby said portion may be inserted through said aperture to project from said support as aforesaid.

said plate being non-insertible within said vertically elongated aperture.

8. In apparatus of the class described, in combination with a vertical support having a vertically elongated transverse aperture, a horizontally arranged and readily demountable shaft-hanger normally mounted upon said support and having a portion projecting from said support, the said portion including an integral structure comprising a horizontally-bored cylindrical member adapted to sleeve a shaft mounted within the hanger, said integral structure also comprising a plate directly mountable upon said support, and said integral structure also comprising a pair of substantially horizontal struts one end of each of said struts being joined to said cylindrical member and the other end of each of said struts being joined to said plate thereby to support said cylindrical member and yet space the same from said support, one of said struts overlying said shaft and the other of said struts lying below said shaft, a cross-section through the first-mentioned strut defining an upright triangle and a cross-section through the second-mentioned strut defining an inverted triangle the vertical distance in a given plane between the upper and lower limits of said portion being less than the horizontal distance in the same plane between the side limits of said portion, the diameter of said member being less than the maximum horizontal dimension of said vertically elongated aperture whereby said portion may be inserted through said aperture to project from said support as aforesaid, said plate being non-insertible within said vertically elongated aperture and said plate being vertically elongated and having in its upper and lower terminal portions transverse apertures, certain of which are adapted to register with said auxiliary apertures in said support and one of which is adapted to lie in line with the prolongation of the horizontal space located between the struts, and an anchoring bolt adapted to coöperate with each of the sets of registering apertures.

10. In apparatus of the class described, in combination with a vertical support having a vertically elongated transverse aperture and a plurality of auxiliary transverse apertures one located above and one below said vertically elongated aperture, a horizontally arranged and readily demountable shaft-hanger normally mounted upon said support and having a portion projecting from said support, the said portion including an integral structure comprising a horizontally-bored cylindrical member adapted to sleeve one end of a shaft mounted within the hanger, said integral structure also comprising a plate directly mountable upon said support, and said integral structure also comprising a pair of substantially horizontal struts, one end of each of said struts being joined to said cylindrical member and the other end of each of said struts being joined to said plate thereby to support said cylindrical member and yet space the same from said support, one of said struts overlying said shaft and the other of said struts lying below said shaft, a cross-section through the first-mentioned strut defining an upright triangle and a cross-section through the second-mentioned strut defining an inverted triangle the vertical distance in a given plane between the upper and lower limits of said portion being less than the horizontal distance in the same plane between the side limits of said portion, the diameter of said member being less than the maximum horizontal dimension of said vertically elongated aperture whereby said portion may be inserted through said aperture to project from said support as aforesaid, said plate being non-insertible within said vertically elongated aperture and being vertically elongated for completely and substantially uniformly overlapping said vertically elongated aperture.

9. In apparatus of the class described, in combination with a vertical support having a vertically elongated transverse aperture and a plurality of auxiliary transverse apertures one located above and one below said vertically elongated aperture, a horizontally arranged and readily demountable shaft-hanger normally mounted upon said support and having a portion projecting from said support, the said portion including an integral structure comprising a horizontally-bored cylindrical member adapted to sleeve one portion of a shaft mounted within the hanger, said integral structure also comprising a plate directly mountable upon said support, and said integral structure also comprising a pair of substantially horizontal struts one end of each of said struts being joined to said cylindrical member and the other end of each of said struts being joined to said plate thereby to support said cylindrical member and yet space the same from said support, one of said struts overlying

said shaft and the other of said struts lying below said shaft, a cross-section through the first-mentioned strut defining an upright triangle and a cross-section through the second-mentioned strut defining an inverted triangle the vertical distance in a given plane between the upper and lower limits of said portion being less than the horizontal distance in the same plane between the side limits of said portion, the diameter of said member being less than the maximum horizontal dimension of said vertically elongated aperture whereby said portion may be inserted through said aperture to project from said support as aforesaid, said plate being non-insertible within said vertically elongated aperture and said plate being vertically elongated and having in its upper and lower terminal portions transverse apertures, certain of which are adapted to register with said auxiliary apertures in said support and one of which is adapted to lie in line with the prolongation of the horizontal space located between the struts, and an anchoring bolt adapted to coöperate with each of the sets of registering apertures.

10. In apparatus of the class described, in combination with a vertical support having a vertically elongated transverse aperture and a plurality of auxiliary transverse apertures one located above and one below said vertically elongated aperture, a horizontally arranged and readily demountable shaft-hanger normally mounted upon said support and having a portion projecting from said support, the said portion including an integral structure comprising a horizontally-bored cylindrical member adapted to sleeve one end of a shaft mounted within the hanger, said integral structure also comprising a plate directly mountable upon said support, and said integral structure also comprising a pair of substantially horizontal struts, one end of each of said struts being joined to said cylindrical member and the other end of each of said struts being joined to said plate thereby to support said cylindrical member and yet space the same from said support, one of said struts overlying said shaft and the other of said struts lying below said shaft, a cross-section through the first-mentioned strut defining an upright triangle and a cross-section through the second-mentioned strut defining an inverted triangle the vertical distance in a given plane between the upper and lower limits of said portion being less than the horizontal distance in the same plane between the side limits of said portion, the diameter of said member being less than the maximum horizontal dimension of said vertically elongated aperture whereby said portion may be inserted through said aperture to project from said support as aforesaid, said plate being non-insertible within said vertically elongated aperture and being vertically elongated for completely and substantially uniformly overlapping said vertically elongated aperture.

said, said plate being non-insertible within said vertically elongated aperture and said plate being vertically elongated and having in its upper and lower terminal portions 5 transverse apertures, certain of which are adapted to register with said auxiliary apertures in said support and one of which is adapted to lie in line with the prolongation of the horizontal space located between the 10 struts, said plate in turn integrally carrying on the side thereof opposite from the side to which are joined said struts a horizontally-

bored cylindrical member adapted to sleeve the other end of said shaft the bore of which member is in prolongation of the last-mentioned aperture in said plate, and an anchoring bolt adapted to coöperate with each of the sets of registering apertures. 15

In witness whereof I have hereunto signed my name in the presence of two witnesses. 20

HUBERT DALTON.

In the presence of—

ABRAM SILVERMAN,
KATHARINE M. SCHELLO.
